Primary Examiner — Bao-Yen T Nguyen(74) *Attorney, Agent, or Firm* — Birch, Stewart, Kolasch & Birch, LLP(57) **CLAIM**

The ornamental design for a computer terminal, as shown and described.

DESCRIPTION

1. Computer terminal

1.1 : Perspective

1.2 : Front

1.3 : Back

1.4 : Left

1.5 : Top

1.6 : Bottom

Reproduction 1.1 is a perspective view of the computer terminal; reproduction 1.2 is a front view thereof; reproduction 1.3 is a back view thereof; reproduction 1.4 is a left view thereof where the right view is a mirror image; reproduction 1.5 is a top view thereof; reproduction 1.6 is a bottom view thereof; this design is for a computer terminal with four displays on the front.
